(57) **CLAIM**

The ornamental design for a hook clip to suspend eyewear or other articles, as shown and described.

DESCRIPTION

FIG. 1 is a perspective view of a hook clip to suspend eyewear or other articles;

FIG. 2 is a front elevation view of the invention;

FIG. 3 is a top plan view of the invention, the bottom plan view being a mirror image;

FIG. 4 is a rear elevation view of the invention;

FIG. 5 is a right side view of the invention;

FIG. 6 is a left side view of the invention;

FIG. 7 is a perspective view of the invention with associated structure shown attached thereto; and,

FIG. 8 is a perspective view of the invention in use.

In the drawings, the broken lines illustrate features that form no part of the claimed design and unclaimed environmental subject matter that form no part of the claim.

1 Claim, 2 Drawing Sheets
